UNITED STATES PATENT OFFICE.

HORACE Y. OTTO, OF WILLIAMSPORT, PENNSYLVANIA.

PAPER-ROLL HOLDER.

No. 840,651.

Specification of Letters Patent.

Patented Jan. 8, 1907.

Application filed November 6, 1906. Serial No. 342,271.

To all whom it may concern:

Be it known that I, HORACE Y. OTTO, a citizen of the United States of America, and a resident of Williamsport, county of Lycoming, State of Pennsylvania, have invented certain new and useful Improvements in Paper-Roll Holders, of which the following is a full and clear specification, reference being had to the accompanying drawings, in

10 which—

Figure 1 is a plan view; Fig. 2, a longitudinal section on the line 2 2 of Fig. 1; Fig. 3, a transverse section on the line 3 3 of Fig. 2; Fig. 4, a transverse section on the line 4 4 of Fig. 2, and Fig. 5 a perspective view of the latch-carrying member of the shaft.

The object of this invention is to improve and simplify the shaft for carrying a roll and to provide a simple form of friction-brake device.

20 The shaft is journaled, as usual, in the arms *a a* of the holding-frame and consists of two members *b* and *c*, each of which is flanged at its outer end at *d* to maintain it in its proper position in the frame. The member *b* is cored out centrally from its inner end toward its outer end, and within this cylindrical chamber is formed an annular groove *e*.

The member *c* of the shaft has its inner end abutted against the inner end of the member

30 *b* and is provided with a reduced extension *f*, which fits within the cylindrical axial recess in the member *b*. This extension *f* extends beyond the annular groove *e*. This member *c* is provided with a longitudinal slot extending transversely through it, and in this slot is mounted a pair of latch members *g*, shouldered at *h*, so that their forward ends shall come flush with the surface of the extension *f*. The extreme forward or inner ends of

40 these latches are provided with beveled noses and hook-like parts *i*, which when the two members of the shaft are telescoped engage against the inner wall of the annular channel *e* and lock the parts together. The latch members have inwardly-extending lugs *j* at their inner ends, by which the latches are pivotally mounted on a transverse pin *k*. The latch members are normally sprung outward by means of a spring *l*, inclosed between

45 them. The outward movement of the latches is limited by a shoulder *m* at the outer end of each latch.

With the construction described it will be observed that the shaft-sections are locked together on the roll by simply pressing the 55 latch members *g* inward sufficiently to permit the hooked ends *i* thereof to pass within the hollow section, and then when the hooks *i* reach the annular groove they snap into the same, and thus lock the parts together. 60

It will be observed that the latch members cannot be reached after the shaft is once slipped into a roll of paper and locked until the paper is entirely unwound from the shaft.

It will be observed that by employing an 65 annular locking-groove *e* and the peculiar latch devices shown the shaft-sections may be telescoped without registering or other adjustment of the parts to each other.

A flat brake-ring *n* surrounds the shaft at 70 one end and is provided with an extension *o*, which extends backwardly and is attached to the inner face of the adjacent arm *a*. A screw *p* is swiveled to the arm or extension *o* and is threaded through the adjacent arm *a* and is 75 provided at its outer end with a winged head *q*, whereby the pressure on the end of the roll of paper may be readily regulated, so that sufficient pressure may at all times be maintained to prevent the paper paying off too 80 rapidly.

Having thus fully described my invention, what I claim, and desire to secure by Letters Patent, is—

A shaft for a paper-roll holder comprising 85 two members, one having an axial recess, which recess is provided with an annular groove or channel at a distance from the inner end of the member, and the other member slotted longitudinally and carrying in 90 said slot a pair of latch members having beveled hooked ends, a spring between the members, a pivot on which both members are pivoted at their outer ends, each member being shouldered to limit its outward movement, 95 substantially as set forth.

In testimony whereof I hereunto affix my signature, in the presence of two witnesses, this 5th day of November, 1906.

HORACE Y. OTTO.
